VALVED FLUID OUTLET

Earl B. Goon, Niles, and Garris W. Heath, Niles
Township, Berrien County, Mich.

Application October 1, 1937, Serial No. 166,816

1 Claim. (Cl. 248—18)

This invention relates to a valved fluid outlet, and particularly to a valved coupling between a permanent gas line and a gas burning utensil.

Heretofore, it has commonly been the practice in piping a building for fuel gas to run the various branch lines from the metered supply line to the approximate locations of the gas burning utensils to be used, as gas heaters, stoves, fireplace fixtures and the like, without regard to appearance, without uniformity and with a mere open threaded end adapted for connection by means of a simple union with the utensil feed line. This is objectionable because it is unsightly, and additionally because it is necessary to shut off supply of gas to all branch lines at the main or supply line in order to disconnect, repair or replace any one utensil. Furthermore, if a utensil such as a heater is disconnected and removed, the bare projecting pipe end is exposed to view, and the projection relation thereof to the wall or floor through which it extends is so unsightly as to materially detract from the appearance of the room.

It is, therefore, the primary object of this invention to provide a novel automatic closing valve structure at the outlet of a fluid pipe line.

A further object is to provide an automatically closing valve structure of simple and inexpensive construction which can be manufactured and assembled with minimum labor and skill.

A further object is to provide a valve of this character which can be readily manipulated for adjustment and cleaning while closed and without requiring closure of the supply line.

A further object is to provide a novel and attractive supply line outlet.

Other objects will be apparent from the description and appended claim.

In the drawing:

Fig. 1 is a perspective view of a room illustrating the application of our improved outlet.

Fig. 2 is a vertical sectional view of a wall illustrating the application of our outlet thereto.

Fig. 3 is a horizontal sectional view illustrating the mounting for our improved outlet.

Fig. 4 is a longitudinal sectional view illustrating our improved valved outlet.

Fig. 5 is an end view of the valved outlet.

Fig. 6 is a longitudinal sectional view illustrating the fitting applicable to our improved outlet.

Fig. 7 is a longitudinal sectional view illustrating the application of a cap to our improved outlet.

Referring to the drawing, the numeral 10 designates the walls, and 11 of the floor of a room,

said walls having the usual base trim board 12 extending along the bottom thereof. In the wall 10 and board 12 we form a small opening 13. Within opening 13 of board 12 we mount a frame 14 whose ends 15 bear against board 12 at opposite sides of said opening and are secured to said board 12 by screws 16. The intermediate portion 17 of frame 14 is rearwardly off-set to project into opening 13. Over the opening 13 and frame 14 is applied a face plate 18 which is also secured to place by screws 16. An aperture 19 is formed centrally in off-set portion 17 of frame 14, and larger aperture 20 is formed in face plate 18 concentric with aperture 19.

We prefer to extend the fluid supply line 21 through floor 11 between the usual studding which supports and spaces the plaster walls 10 of adjoining rooms, and mount an elbow 22 thereon opposite wall opening 13. To this elbow we connect valve housing 23 which preferably comprises an interiorly screw threaded tubular portion 24, for connection with the elbow, and a concentric reduced exteriorly screw threaded portion 25 projecting through frame aperture 19 and forming an exterior shoulder 26 adapted to bear against the inner face of frame portion 17 at the margin of aperture 19. The housing 23 is also provided with an annular interior shoulder 27 at the junction of housing portions 24 and 25 which forms a valve seat. Within housing portion 24 is positioned a valve disc 28 adapted to seat marginally against shoulder 27. A valve stem 29 projects centrally and axially from disc 28 into housing portion 25 to extend substantially the full length of said housing portion, said stem preferably being formed integrally with said disc 28. Stem 29 is screw threaded at its outer end portion 30, and is provided with a transverse groove 31 in its end. A narrow elongated plate 32, preferably having arcuate ends concentric with housing portion 25 and fitting therein with a slight clearance, is screw threaded on the end valve stem 29 at its center. Between the interior housing shoulder 27 and the plate 32 is interposed a coil spring 33 to normally urge plate 32 outwardly and thereby seat valve disc 28 on shoulder 27. The parts are so arranged that the outer face of plate 32 is normally positioned slightly inwardly of the end of housing portion 25. A nut 34 is threaded on reduced housing portion 24 to urge the same outwardly relative to frame 14 so that said frame is gripped between the nut and shoulder 26 to rigidly hold said housing in place. The housing portion 25 terminates adjacent face plate 18, so that when a cap 35, preferably having a gasket ring

36 against which the end of portion 25 may bear, is threaded thereon to seal the housing, the same will project only slightly, if at all, beyond said face plate. The face plate aperture 20 is preferably of a size just sufficient to permit tightening and release of said cap or of a fitting.

5 For connection of the outlet with the feed conduit of a utensil, we provide a tubular fitting 37 of a size which will fit freely in housing portion 10 25. In spaced relation to one end of this fitting 37, we provide an exterior shoulder 38, as by an annular bead. A nut 39 adapted for threaded connection with valve housing portion 25 fits loosely around the end of fitting 37 and is provided with an inturned flange 40 adapted to bear 15 against shoulder 38. Within the nut 39 is mounted a ring gasket 41 adapted to seat against shoulder 38. The shoulder 38 of fitting 37 and the nut 39 are so proportioned and arranged that the 20 outer edge of nut 39 will project beyond the outer edge of the fitting when flange 40 abuts shoulder 38.

It will be seen from the above that, by having 25 the valve arrangement permanently connected to the gas line, the same prevents leakage of gas when a utensil is disconnected and the supply line is uncapped. It is, therefore, unnecessary to close the main gas line when effecting a connection or disconnection at any branch thereof. 30 Also, the work incident to opening and closing of all pilot lights in one system and relighting the same incident to reopening the system, is avoided when working at any branch thereof.

The outlet is attractive in appearance by virtue 35 of the face plate 18, particularly when a cap 35 for sealing the outlet matches the face plate and serves substantially to fill face plate aperture 20.

The parts of the fitting 37 and plate 32 of the 40 outlet are so proportioned and arranged that, in connecting the same, the nut 39 can be well started on threaded outlet portion 25 before the end fitting 37 is urged by said nut into engagement with plate 32 to unseat valve 28. In this

way the leakage of gas incident to valve opening in effecting the connection is reduced to a minimum which occurs only for the length of time necessary for tightening the nut to effect sealing engagement between outlet portion 25 and gas- 5 ket 41. Likewise, upon disconnection of the fitting and the outlet, the valve 28 is permitted to close before the nut 39 is released from outlet part 25.

The time of opening and closing of the valve 10 28 in effecting the connection and disconnection aforesaid is readily adjustable while maintaining valve 28 closed by changing the position of plate 32 on valve stem 29, as is readily achieved by the screw threaded interconnection of said parts, 15 and the valve stem groove 31 by means of which the valve stem may be manipulated or controlled during relative rotation of the same and plate 32. It will also be seen that stem groove 31 affords means for rotating valve 28 on its seat for release 20 of dirt particles which may be lodged between the valve and its seat without interrupting the gas service or requiring disassembly of parts. The valve structure and assembly also has the advantages of simplicity of construction, very few 25 component parts, inexpensiveness, and quick and simple assembly in its housing.

We claim:

In a valved fluid outlet, a housing having an annular internal projection spaced from its end, 30 a valve adapted to seat on said projection and having an integral outwardly extending stem threaded at its outer end, a narrow cross piece threaded on said stem and freely shiftable longitudinally within said housing and adjacent to 35 the end of said housing, and a coil spring bearing against said projection and said cross piece at its ends, wherein said stem has a grooved end adjacent the end of said housing to accommodate manipulation of said valve and adjustment of 40 the position of said cross piece within said housing.
